UNITED STATES PATENT OFFICE

94,126

DESIGN FOR AN OIL FIRED SPACE HEATER

Harold L. Finley, La Porte, Ind., assignor to The Lonergan Manufacturing Co., La Porte, Ind., a corporation of Indiana

Application November 5, 1934, Serial No. 53,899

Term of patent 14 years

To all whom it may concern:

Be it known that I, Harold L. Finley, a citizen of the United States, residing at La Porte, in the county of La Porte, and State of Indiana, have invented a new, original, and ornamental Design for an Oil Fired Space Heater, of which the following is a specification, reference being had to the accompanying drawing, forming a part thereof.

The figure shows a perspective view of an

oil fired space heater illustrating my new design, the heater being substantially rectangular in outline with set-back portions forming a short tower which is provided with a grill enclosing the upper end.

I claim:

The ornamental design for an oil fired space heater substantially as shown and described.

HAROLD L. FINLEY.
